UNITED STATES PATENT OFFICE.

JUANITA MILLER, OF OAKLAND, CALIFORNIA.

DESIGN FOR A DOLL.

Application filed June 9, 1926. Serial No. 17,992. Term of patent 3½ years.

To all whom it may concern:

Be it known that I, JUANITA MILLER, a citizen of the United States, residing at Oakland, in the county of Alameda and State of California, have invented a new, original, and ornamental Design for Dolls, of which the following is a specification, reference being had to the accompanying drawing, forming part thereof.

The first figure is a plan view of a doll, showing my new design.

The second figure is an edge view of the doll.

I claim:

The ornamental design for a doll, as shown.

JUANITA MILLER.
